(57) **CLAIM**

The ornamental design for a wireless voice/data communicator, as shown and described.

DESCRIPTION

FIG. 1 is a front and top perspective view of the wireless voice/data communicator;

FIG. 2 is a top plan view of the wireless voice/data communicator;

FIG. 3 is a rear plan view of the wireless voice/data communicator;

FIG. 4 is a front elevational view of the wireless voice/data communicator;

FIG. 5 is a rear elevational view of the wireless voice/data communicator;

FIG. 6 is a right side elevational view of the wireless voice/data communicator; and,

FIG. 7 is a left side elevational view of the wireless voice/data communicator.
